UNITED STATES PATENT OFFICE.

GEORGE W. RAUSCHENBERGER, OF BUTLER, PENNSYLVANIA.

APPARATUS FOR COATING CANDIES, CAKES, ETC.

Application filed February 23, 1922. Serial No. 538 672.

My invention relates to apparatus for coating confections, cakes, or blocks of ice-cream in the making of what are commonly known as "Eskimo pies".

5 The object of my invention is to provide a simple and efficient form of apparatus by means of which confections, cakes, etc. may be coated with a different material, such as icing or chocolate, and the operations carried 10 on so rapidly and expeditiously as to give the machine a great capacity and do away with the manual labor which has heretofore formed a large part of such coating operations in factories for the manufacture of such 15 articles.

In the accompanying drawing, Fig. 1 is a longitudinal view of my improved apparatus partly in section; Fig. 2 is a plan view of same; Fig. 3 is an enlarged view of the tongs 20 and the manner of opening same; Fig. 4 is a like view showing the tongs closed; Fig. 5 is a side view of the tongs; Figs. 6 and 7 show the details of the tongs-opening device; Fig. 8 is a detail of the receiving guide; and Figs. 25 9, 10 and 11 show a modified form of my invention.

In the drawings the numeral 2 designates a suitable floor or foundation upon which my improved apparatus is set up. At one end is 30 the frame 3 and at the other end the standard 4. Sprocket-wheels 5 and 6 are mounted in said frame 3 and standard 4, respectively. The sprocket-wheel 5 is mounted on the driven shaft 5^a. A suitable sprocket-chain 35 or belt 7 of any suitable form passes around the sprocket-wheels 5 and 6, and under the guide-sheave 7^a, thereby forming inclined portions in said belt.

Secured at intervals on the chain 7 are the 40 tong-frames 8 with the downwardly extending arms 9 to which the tongs 10 are connected, the pin 11 connecting the arms of said tongs forming the pivot on which said tongs open and close. A spring 12 connects the 45 upper ends of the tong-arms, and said spring acts normally to hold said tongs in closed position. Stops 13 at the upper ends of said arms are adapted to engage the extension 9 to control the closing movement of said tongs, 50 said stops being adjustable for this purpose.

The lower arms of the tongs carry the 55 prongs 14 which are adapted to engage the article to be coated, and where such an article is somewhat elongated, as in the case of a block of ice-cream 15, a pair of such grippers may be used on each arm, as clearly indicated

in Fig. 5. These prongs may be made of a wire of proper rigidity, such as piano-wire, and as they are simply inserted in seats in the tongs, they may be readily renewed from 60 time to time as they may wear out.

The articles to be coated are delivered to the endless belt 16 mounted on the sheaves 17 and 18, the shaft 19 of the sheave 18 being driven by a chain 20 on a sprocket 21 on the 65 shaft 5^a engaging the sprocket 22 on the shaft 19.

Where the material to be coated is cut into the required length, the knife 23 is provided which is moved up and down in suitable 70 guides 24. A lever 25 is connected to the link 26 connected to the knife, said lever being pivoted at 27. A link 28 connects said lever with the arm 29 pivoted at 30. The arm 29 carries the roller 31 which is in the path of 75 movement of the arm 32 on the shaft 5^a. Each time the shaft 5^a makes a rotation the arm 32 engages the arm 29 and said arm is moved, and through the link 28 and lever 25 the knife is lowered to cut the material. A 80 spring 33 is connected to the lever 25 and to the frame, said spring acting to normally hold the knife in raised position.

As the articles to be coated are carried along by the conveyer 16 they are directed 85 into a suitable inclined guide or support 34 which has the flaring inlet 35. This guide 34 is supported on an incline, and while in this guide the tongs take hold of the article, and to provide for the opening of the tongs at 90 this point the tongs-opener 36 is provided with the tapering portion 37. As the tongs approach the guide 34 they are opened gradually by engaging the tapered portion 37 of the tongs-opener, and when they reach 95 the wide portion of said opener the tongs are opened to their full extent and in position to grasp one of the articles to be coated in the guide 34. Just as soon as the tongs leave the opener 36 the spring 12 closes the tongs and the prongs engage the article at opposite 100 sides, as indicated in Figs. 4 and 5 just before the article leaves the guide 34. When the article leaves the guide 34 it is supported wholly by the chain 7.

A tank 38 is located in the depression 39 in the floor, and said tank contains the chocolate 40, or other coating material, and suitable heating apparatus may be provided for maintaining the chocolate to proper consistency for coating. The article is carried 105 through the bath, and when it emerges there-

from it continues to move along, and during this movement the coating material is cooled and hardens around the article, so that when the article reaches the conveyer 41 it is ready 5 to be released from the tongs and dropped on said conveyer to be carried off to the wrappers. Accordingly at this point a tongs-opener 42 is located which opens the tongs, and after passing said opener the tongs are 10 then closed until they come around into position to be opened by the opener 36 to take hold of another article.

In Figs. 9, 10 and 11 I have shown a modified form of my invention. Instead of the 15 carrying devices being in the form of tongs with two arms, I have illustrated a single spring-arm 44 which is secured by the rivet 45 to the belt 7. This arm has the gripping fingers or prongs 46. The guide 47 receives 20 the article to be coated, as before, and the inner wall 48 of said guide forms an abutment to support the article when the prongs 46 are forced into said article. The cam 49 in the path of the arm 44 acts to move said 25 arm outwardly, and when said arm passes beyond said cam it springs inwardly and the prongs are forced into the article. The stop portion 50 of the cam 49 controls the inward movement of said arm and prevents the distortion or indenting of the article.

I include within the scope of my invention any kind of a retaining device carried by the belt which will support the articles to be coated while passing through the coating 30 material.

By my invention I provide a very simple and efficient form of apparatus by which the coating is done in quick succession, and the 35

manual labor heretofore employed for this purpose is dispensed with, thereby greatly 40 reducing the cost and furthermore greatly increasing the capacity. The machine is particularly adapted for the making of what are commonly known as "Eskimo Pies", as the ice cream as it is delivered to the endless 45 conveyer 16 is cut in suitable lengths or blocks 15 and delivered to the guide 34 to be grasped by the tongs as they come around, and each piece is carried along and through the hot chocolate to receive the proper coating, so 50 that when it emerges therefrom it will be thoroughly coated and the chocolate will be given a chance to cool and set before it reaches the conveyer 41.

What I claim is:

1. In apparatus for coating confections, cakes, etc., the combination of an endless belt, a plurality of arms carried by said belt, inwardly extending prongs on said arms, means for separating said arms, means for moving 60 said arms inwardly to engage the articles to be coated by said prongs, and a receptacle for containing the coating material in the path of said articles.

2. In apparatus for coating confections, cakes, etc., the combination of an endless belt, a plurality of spring-actuated arms having inwardly extending prongs adapted to engage the articles to be coated, and a receptacle for containing the coating material 70 in the path of said articles.

In testimony whereof, I, the said GEORGE W. RAUSCHENBERGER, have hereunto set my hand.

GEORGE W. RAUSCHENBERGER.
